UNITED STATES PATENT OFFICE

153,157

DESIGN FOR A GAMEBOARD

Joe W. McFerran, Detroit, Mich.

Application May 20, 1947, Serial No. 139,167

Term of patent 14 years

(Cl. D34—5)

To all whom it may concern:

Be it known that I, Joe W. McFerran, a citizen of the United States and a resident of Detroit, county of Wayne, and State of Michigan, have invented a new, original, and ornamental Design for a Game Board, of which the following is a specification, reference being had to the accompanying drawing, forming part thereof.

In the drawing the figure is a plan view of the playing surface of the game board, showing my invention.

The article is of no appreciable thickness and the features are flush with the surface. The dominant features of my design are shown in solid lines in the drawing.

I claim:

The ornamental design for a game board, as shown and described.

JOE W. McFERRAN.
